US00D943058S

(12) **United States Design Patent** (10) **Patent No.:** **US D943,058 S**
(45) **Date of Patent:** **** Feb. 8, 2022**

(54) **FILTER CARTRIDGE**

- (71) Applicant: **Megadyne Medical Products, Inc.**,
Draper, UT (US)
- (72) Inventors: **Shawn K. Horner**, Woods Cross, UT
(US); **Chad S. Frampton**, American
Fork, UT (US); **Steven D. Andrews**,
West Jordan, UT (US)
- (73) Assignee: **Megadyne Medical Products, Inc.**,
Draper, UT (US)
- (**) Term: **15 Years**
- (21) Appl. No.: **29/733,877**
- (22) Filed: **May 7, 2020**

Related U.S. Application Data

- (63) Continuation of application No. 29/627,793, filed on
Nov. 29, 2017, now Pat. No. Des. 886,976.
- (51) **LOC (13) Cl.** **23-01**

(57) **CLAIM**

The ornamental design for a filter cartridge, as shown and described.

DESCRIPTION

FIG. 1 is a perspective view of the filter cartridge showing the new design;

FIG. 2 is a front end elevational view of the filter cartridge;

FIG. 3 is a back end elevational view of the filter cartridge;

FIG. 4 is a left side elevational view of the filter cartridge;

FIG. 5 is a right side elevational view of the filter cartridge;

FIG. 6 is a top plan view of the filter cartridge;

FIG. 7 is a bottom plan view of the filter cartridge;

FIG. 8 is another perspective view of the filter cartridge

showing the new design;

FIG. 9 is a front end elevational view of the filter cartridge;

FIG. 10 is a back end elevational view of the filter cartridge;

FIG. 11 is a left side elevational view of the filter cartridge;

FIG. 12 is a right side elevational view of the filter cartridge;

FIG. 13 is a top plan view of the filter cartridge; and,

FIG. 14 is a bottom plan view of the filter cartridge.

The broken lines shown in the drawings are for the purpose of illustrating portions of the filter cartridge that for no part of the claimed design.

1 Claim, 8 Drawing Sheets
